UNITED STATES PATENT OFFICE.

HENRY WILVERTH, OF ST. CHARLES, KENTUCKY.

COAL-EXCAVATOR.

SPECIFICATION forming part of Letters Patent No. 252,565, dated January 17, 1882.

Application filed June 22, 1881. (No model.)

To all whom it may concern:

Be it known that I, HENRY WILVERTH, of St. Charles, in the county of Hopkins and State of Kentucky, have invented a new and 5 Improved Coal-Excavator, of which the following is a full, clear, and exact description.

This invention relates to that class of excavators in which a rod of iron with a pick projecting in line from its end is used, and its object is to enable the operator to make a long and deep trench.

The invention consists of a peripherally-grooved wheel journaled in a swiveled trunnion-bed or pillow-block and supporting in its groove 15 the excavating rod and pick; and it further consists of an adjustable weight secured on one end of said rod to counterbalance the weight of the pick on the opposite end, all of which will be hereinafter set forth.

20 Figure 1 is a side elevation of the device. Fig. 2 is an enlarged vertical section of the same on line *xx*, Fig. 1. Fig. 3 is a plan of the same. Fig. 4 represents views of another style of pick that is used with the device.

25 Similar letters of reference indicate corresponding parts.

In the accompanying drawings, A represents a portable bed-plate, preferably of wood, provided with spikes *a* on its under side to 30 secure it in any desired position. Secured on either face of the bed-plate A by bolts and nuts *b b* is a centrally-perforated metal plate, B, to increase the strength and durability thereof.

35 C represents the trunnion-bed or pillow-block, supported in an upright position by the entrance of its spindle *c* into and through the center of the plates A B B, and affording bearings for the trunnions on the shaft D' of 40 the grooved wheel D, that is designed to revolve in a vertical plane and support the rod or bar E that carries the pick F.

A pin, *m*, is passed at right angles through the spindle *c*, beneath the upper plate, B, to 45 hold the trunnion-block C in place, and a circular excavation, *c'*, is made in the bed-plate A, to afford room for the pin *m* when the block C is revolved. This rod or bar E has on one end an enlarged socket, G, in which a 50 pick, F, is secured by a key, *d*, and on its other end a sliding adjustable weight, H, is secured by a set-screw, *f*, which weight H is designed to counterbalance the weight of the pick F, so that the latter and its rod E shall be kept 55 in suitable position when in operation. The

device is operated by giving a reciprocating longitudinal motion to rod and pick E F, and being supported on the grooved swiveled wheel D, they can be moved back and forth with but little labor, and can be swung in 60 horizontal and vertical planes to excavate long and deep trenches in the coal or other material to be operated upon; and the bed-plate A can be secured at any desired inclination, so that the pick F can be made to operate to form trenches at any required angles, therein possessing great advantages over those coal-excavators not having swiveled rolling supports for their picks and rods.

This pick that is most effective for ordinary 70 coal-excavation has a double-chisel-pointed cutting end, as shown in Fig. 1; but the pick shown in Fig. 4 or any other convenient form may be used with this device.

I am aware that it is not entirely new to support a reciprocating mining-tool upon grooved wheels, and therefore do not broadly claim a carriage of such construction.

Having thus described my invention, what I claim, and desire to secure by Letters Patent, 80 is—

1. In a coal-excavator, the combination, with the rod and pick E F, of the swiveled block C and the supported grooved wheel D, substantially as herein shown and described, whereby 85 said rod and pick are supported and easily operated to excavate long and deep trenches in any direction, as set forth.

2. In a coal-excavator, the combination, with the pick-rod E and pick F, supported on the 90 fulcrum-wheel D, of the counter-balance H, substantially as and for the purposes described.

3. In a coal-excavator, the combination, with the bed-plate A, provided with face-plates B, of the trunnion-bed or pillow-block C, provided 95 with a spindle, *c*, substantially as herein shown, and for the purpose described.

4. In a coal-excavator, the combination, with the swiveled pillow-block C, of the grooved wheel D, substantially as herein shown and 100 described.

5. In a coal-excavator, the combination, with the rod and pick, of a vertically and horizontally revolving support, substantially as herein shown and described, whereby any desired 105 direction may be given to the pick, as set forth.

HENRY WILVERTH.
